PINKING MACHINE

Lester S. Rod, Dallas, Pa.

Application August 3, 1940, Serial No. 350,705

3 Claims. (Cl. 164—50)

This invention relates to pinking machines and has as its object the production of a new and improved machine of this type.

More particularly stated, the object of this invention is to produce a pinking machine which shall be relatively simple in construction and which shall be positive in its operation.

The foregoing as well as other objects are each obtained in the pinking machine shown in the drawings which form a part hereof and which will now be described.

In said drawings, Figure 1 is a front view of the novel pinking machine as it normally appears when not in operation.

Figure 2 is a side view of the same.

Figure 3 is a plan view of the same.

Figure 4 is an enlarged side view partly in section. A portion of the pedestal intermediate its ends has been broken away to permit the showing of the remaining parts on as large a scale as possible. The full lines show the respective positions of the movable elements at the end of the pinking operation and the dot and dash lines show the respective positions of these movable elements at the beginning of the pinking operation.

Figure 5 is an enlarged front view partly in section of the pinking machine. A portion of the pedestal intermediate its ends has been broken away to permit the showing of the remaining parts on as large a scale as possible. The full lines show the respective positions of the movable elements at the end of the pinking operation and the dot and dash lines show the respective positions of these movable elements at the end of the pinking operation.

Figure 6 is an enlarged section taken along the line 6—6 of Figure 1.

Figure 7 is a section taken along the line 7—7 of Figure 6.

Figure 8 is a section taken along the line 8—8 of Figure 6.

Figure 9 is a section taken along the line 9—9 of Figure 5.

Figure 10 is a section taken along the line 10—10 of Figure 9.

Figure 11 is a section taken along the line 11—11 of Figure 9.

Referring more particularly to the drawings, wherein similar reference numerals denote similar parts, reference numeral 1 designates the pinking machine as a unit. The pinking machine 1 consists of a base 2, a pedestal 3 carried by said base 2, a head 4 carried by said pedestal 3, a platform 5 carried by a shaft 6 which is movably mounted in the pedestal 3, a treadle 7 mounted in said pedestal 3 for actuating said shaft 6, and shear elements 8 and 9 carried by the head 4 and platform 5 respectively.

The base 2 is hollow and consists of a flange

10 which rests upon the floor which supports the machine and a standard 11 which extends upwardly from said flange 10. The standard 11 has formed thereon the spaced lugs 12 which serve as bearing members for the pin 13 which extends through the boss 26 formed in the lever 24 and on which said treadle rocks. The standard 11 has formed therein near the upper part thereof the floor 14 which separates the hollow base into an upper chamber 15 and a lower chamber 16. The arm 28 of the lever 24 extends into the lower chamber 16 through a suitable aperture 17 formed in the wall 18 of the standard 11 and contacts the lower end 31 of the shaft 6 which extends through a suitable aperture 19 formed in the floor 14. The upper chamber 15 receives the lower end 34 of the pedestal 3 the lower edge 35 of which rests upon and is supported by the surface 20 of the floor 14. A suitable set screw 21 extends through the wall 18 of the standard 11 and locks the pedestal 3 against rotative motion relatively to the standard 11. The flange 10 has suitable apertures 22 formed therein through which extend screws 23 which anchor the base 2 to the floor of the room in which the pinking machine is mounted.

The treadle 21 consists of a lever 24 and a tread plate 25 attached near the free end of the arm 27 of the lever 21. The lever 24 has a hollow boss 26 formed therein through which the pin 13 extends and which serves to divide the lever 24 into the tread plate carrying arm 27 and the shaft actuating arm 28. The pin 13 extends through a suitable aperture 30 formed in each

35 of the lugs 12, through the bore 29 formed in the boss 26 and has a bore 32 formed therein near each of the ends thereof which receives the cotter pin 33 which holds the pin 13 against lateral movement relatively to the standard 11.

40 The pedestal 3 is a hollow cylindrical member the external diameter of which is such that its lower end 34 will be snugly received within the upper chamber 15 of the standard 11 and such that its upper end 36 will be snugly received within the chamber 80 formed in the boss 79 of the head 4. The internal diameter of the pedestal 3 is such as will permit it to freely house the shaft 6.

45 The shaft 6 consists of the body portion 38 which extends upwardly from the lower chamber 16 in the standard 11, through the aperture 19 in the floor 14 of the standard 11, through the pedestal 3, and through a suitable bore formed in the boss 79 of the head 4, and terminates at its

50 upper end in a threaded portion 39 which extends through a suitable aperture formed in the base plate 44 of the platform 5 and is attached to said base plate by means of a nut 41. The threaded portion 39 is of less diameter than the body portion of the shaft with the result that a shoulder

55 is formed on the shaft 6 just below the threaded portion 39. The shoulder 42 is of such diameter that it will not pass through the aperture 44 of the base plate 44 of the platform 5 but will be received therein and will bear against the inner surface of the base plate 44 to hold the shaft 6 in the platform 5.

40 is formed on said body portion at the point where the threaded portion begins. This shoulder 40 abuts the lower surface 51 of the base plate 48. The body portion 38 of the shaft 6 has attached thereto the collar 42 by means of a suitable set screw 43 at a point intermediate its ends. The upper surface 44 of the collar 42 serves as the bearing member for the lower end 46 of the helical spring 45 which is positioned around the shaft 6. The upper end 47 of the 10 spring 45 bears against the roof 93 of the chamber 80 formed in the boss 79 of the head 4.

The platform 5 consists of a base plate 48 and an upper plate 49 joined together by suitable nuts and bolts 50. The upper plate 49 has attached thereto the guard 58 by means of suitable screws 59. The base plate 48 has attached thereto by means of suitable screws 57 the trough 56 which received the sheared fragments of the garment being pinked. The base plate 48 also has attached thereto by means of nuts 41 the two spaced apart guide pins 52. Each of said pins 52 consists of a body member 53 which terminates at its upper end in a threaded portion which extends through a suitable aperture formed in the base plate 48 and on which the nut 41 is threaded. The threaded portion 54 of each guide pin 52 is of less diameter than the body portion 53 with the result that a shoulder 55 is formed on the body portion at the point where the threaded portion 54 begins. This shoulder abuts the lower surface 51 of the base plate 48. The body portion 53 of each of said guide pins 52 is received within a suitable bore formed in the boss 79 of the head 4. The base plate 48 also has attached thereto by means of suitable screws 60 the fixed member 61 of the shear element 9.

The shear element 9 consists of said fixed member 61 and the cutting member 62 which has a certain limited motion in a horizontal plane relative to the fixed member 61. The cutting member 62 is attached to the fixed member 61 by means of the shoulder screws 63-64. The shoulder screws 63-64 are identical in structure and differ only in the distance which their respective surfaces 65 and 66 are from the surface 67 of the fixed member 61. As is shown in Figures 6 to 11 the outer surface 65 of the shoulder screw 63 is substantially at the surface 67 of the fixed member 61 whereas the surface 66 of the shoulder screw 64 is at a distance from said surface 67. This is due to the fact that the recess 68 which receives the shoulder screw 63 is not as deep as the recess 69 which receives the shoulder screw 64. As a result of this structure, the cutting member 62 is positioned so that its surface 70 contacts the surface 71 of the fixed member 61 at its end 72 and is at a distance from said surface at its opposite end 73 when the machine elements are in the non-pinking or normal position. The cutting member 62 is normally urged to this position and held there by means of the leaf spring 74 which may be adjusted to the tension desired by manipulating the screw 75. Access to this screw is had through a suitable cut-out formed in the upper plate 49 and which is normally closed by the cover 76.

The head 4 consists of an inverse C-shaped arm 77 which has a cross-piece 78 attached thereto at the upper end thereof and which terminates in a boss 79 at the lower end thereof. The boss 79 has the chamber 80 formed therein which receives the upper end 38 of the pedestal 6. The head 4 is held against rotative motion rela-

tively to the pedestal 6 by means of suitable screws 81. The cross-bar 78 is attached to the upper end of the arm 77 by means of suitable screws 82. The cross-bar 78 is channeled and offset at its lower end to form a member 83 which is the fixed member of the shear element 8. The fixed member 83 of the shear element 8 has attached thereto by means of suitable shoulder screws 85 and 86 the cutting member 84 of said shear element. The shoulder screws 85 and 86 are similar in structure and function to the shoulder screws 63 and 64. The fixed member 83 has formed therein recesses 87 and 88 which receive the shoulder screws 85 and 86 respectively and which are similar in structure and function to the recesses 68 and 69 respectively formed in the fixed member 61 of the shear element 8. As a result of this structure the cutting member 84 of the shear element 8 is positioned relatively to the fixed member 83 of said shear element in exactly the same manner as the cutting member 62 of the shear element 9 is positioned relatively to its fixed member 61. That is, the face 89 of the cutting member 84 contacts the face 90 of the fixed member at its end 91 and said face 89 is at a distance from said face 90 at its end 92 when the machine elements are in the inactive or non-pinking position. The cutting member 84 is urged to this position and held there by the leaf spring 74 which may be adjusted to the tension desired by manipulating the screw 75. It is to be noted that suitable ports, such as 96, are provided wherever necessary or desirable to permit the introduction of a suitable lubricant to reduce to a minimum the friction between moving parts.

As is best seen in Figures 1 and 5, the cutting member 84 is so attached to the fixed member 83 that its lower edge forms an acute angle with the plane of the surface 93 of the upper plate 49 of the platform 5. As is best seen in Figures 2, 6, 7, and 8, the shear element 8 is so positioned relatively to the shear element 9 that the first tooth A of the cutting member 84 of the shear element 8 will mesh with the first tooth A' on the cutting member 62 of the shear element 9 when the platform 5 is raised to the point where the end 72 of the cutting member 62 first contacts the end 91 of the cutting member 84. But the remaining teeth in each of said cutting bars would not mesh if they were to be projected into a normal plane. This, of course, is due to the fact that the cutting members 62 and 84 are mounted angularly to their respective fixed members 61 and 83. As is best seen in Figures 2, 7 and 8, the shear element 8 does not contact the shear element 9 and the treadle 7 is in the raised position when the machine is in the non-pinking or normal position.

Although the manner in which my novel device functions is believed to be obvious from the foregoing disclosure yet for the purpose of obviating any possibility of a misunderstanding the following detailed description is here given.

Let it be assumed that the operator desires to pink the ends of a pair of trousers. He therefore places the trousers upon the surface 94 of the upper plate 49 so that the free ends of the trousers project a short distance beyond the edge of the cutting member 62 of the shear element 9. The operator then places his foot upon the platform 25 of the treadle 7 and exerts pressure thereon in a downward direction, schematically illustrated by the arrow P in Figures 2 and 4. As a result, the treadle 7 moves from the dot and

dash line position shown in Figure 4 to its full line position in said figure. During this movement the arm 28 of the treadle lever 24 is contacting the lower end 31 of the shaft 6 and is raising said shaft causing it to move from its dot and dash line position in Figure 4 to its full line position in said figure. As the shaft 6 rises it carries with it the platform 5 which is attached thereto. As the platform 5 rises it reaches a point where the first tooth A of the cutting member 62 of the shear element 9 meshes with the first tooth A' formed on the cutting member 84. As these teeth mesh, the cutting members 62 and 84 of which they are integral parts move from their respective positions shown in Figure 6 to their respective positions shown in Figure 9 a distance sufficient to permit the tooth on the cutting member 62 immediately adjacent A to mesh with the tooth on the cutting member 84 immediately adjacent A'. As these teeth mesh the cutting members 62 and 84, of which they are integral parts, move from their respective positions shown in Figure 6 to their respective positions shown in Figure 9 a distance sufficient to permit the succeeding tooth on the cutting member 62 to mesh with the succeeding tooth on the cutting member 84. This continues as the platform 5 continues to rise upwardly from its dot and dash line position in Figures 4 and 5 to its full line position in said figures. When the platform reaches the position shown by the full lines in Figures 5 and 6 all of the teeth on the cutting member 62 have meshed with all of the teeth on the cutting member 84. (The plan view of the teeth when fully meshed is shown in Figure 9 and the plan view of the teeth as they appeared before the platform began to rise is shown in Figure 6. Movement of the cutting members 62 and 84 from their respective positions shown in Figure 6 to their respective positions shown in Figure 9 is made possible because of the angular mounting of the cutting members 62 and 84 relative to their respective fixed members 61 and 83 and sufficient clearance or proper fitting is provided between the shoulder screws 63, 64, 85 and 86 and the fixed members 61 and 83 through which they extend.) As the platform 5 rises during the course of the movement described in this paragraph it carries with it the trousers positioned thereon which are "pinned" by the cooperating shear elements 8 and 9. The material cut-off in the pinking operation falls upon the trough or chute 56 and slides down to a waste-box (not shown). As soon as the pinking operation is completed, the operator removes his foot from the treadle. The force of gravity, plus the pressure of the helical spring 55 forces the shaft 6 and platform 5 carried thereby to move from the full line position shown in Figures 4 and 5 to their respective dot and dash line positions in said figures. In the course of this downward motion, the cutting members 62 and 84 reverse the movements described in the preceding paragraph and go from their respective positions shown in Figures 9 to 11 to those shown in Figures 6 to 8. The shock due to the rapid descent of the platform 5 is absorbed by the rubber pads 95 which are positioned on the upper surface 97 of the boss 79 and on which the platform rests when it is in the lowered or normal position shown by the full lines in Figures 1 to 3 and the dot and dash lines in Figures 4 and 5.

The foregoing description is to be understood as being by the way of illustration only and not by the way of limitation since many changes may be made in the structure here shown without departing from the spirit of my invention. For this reason, it is my desire that the claims which are hereunto appended for the purpose of defining my invention should be limited only by the prior art.

Having described my invention, what I claim as new and useful is:

1. In a pinking machine comprising a base member and a platform movable relatively to said base member from a non-shearing to a shearing position—a pair of shear elements, one carried by said base member and the other by said platform; each of said shear elements comprising a fixed member, guide pins carried by said fixed member, a toothed cutting member mounted on said pins at an angle to said fixed member for movement relatively to said fixed member during the shearing operation, and means for normally urging one of the ends of said toothed cutting member away from said fixed member thereby causing said toothed cutting member to form an angle with said fixed member when the shearing elements of said pinking machine are in the non-shearing position.
2. In a pinking machine comprising a base member and a platform movable relatively to said base member from a non-shearing to a shearing position—a pair of shear elements, one carried by said base member and the other carried by said platform; each of said shear elements comprising a fixed member, guide pins carried by said fixed member, a toothed cutting member mounted on said pins at an angle to said fixed member for movement relatively to said fixed member during the shearing operation, and means for normally urging one of the ends of said toothed cutting member away from said fixed member thereby causing said toothed cutting member to form an angle with said fixed member when the shearing elements of said pinking machine are in the non-shearing position, said toothed cutting members being positioned at an angle to each other and so that their teeth will mesh at one of their adjoining ends and overhang at the other of their adjoining ends when said toothed cutting members first contact in the course of the motion of said platform from its non-shearing to its shearing position.
3. In a pinking machine comprising two members, one movable relatively to the other from a non-shearing to a shearing position—a pair of shear elements, one carried by one of said members and the other carried by the other of said members and each of said shear elements having a toothed cutting edge; at least one of said shear elements comprising a fixed member and a toothed cutting member forming an acute angle with said fixed member and being mounted for movement relatively to said fixed member during the shearing operation, and means for normally urging one of the ends of said toothed cutting member away from said fixed member thereby causing said toothed cutting member to form said acute angle with said fixed member when the shearing elements of the pinking machine are in the non-shearing position.

LESTER S. ROD.
